UNITED STATES PATENT OFFICE.

WELLINGTON W. MUIR, OF LOCKPORT, NEW YORK.

PROCESS OF AND APPARATUS FOR COOLING INTERNAL-COMBUSTION ENGINES.

Application filed August 16, 1922, Serial No. 582,220. Renewed April 8, 1927.

This invention relates to cooling systems for internal combustion engines and has for its object to provide a means, as well as a procedure which will be more efficient in action and more certain in operation than those heretofore proposed.

With these and other objects in view the invention consists in the novel steps and combinations of steps constituting the process and in the novel parts and combinations of parts constituting the apparatus, all as will be more fully hereinafter disclosed and particularly pointed out in the claims.

Referring to the accompanying drawings forming a part of this specification in which like numerals designate like parts in all the views:

The figure is a diagrammatic partially sectional view of a cooling system made in accordance with this invention.

1 indicates the jacket of an internal combustion engine, 2 a radiator, 3 a passage from said jacket to a tank 4 located above the radiator 2, 5 a passage leading from said tank 4 into the space 6 above said radiator 2, 7 water tubes leading from said space 6 into the chamber 8 at the bottom of said radiator, 9 a pipe or passage leading from said tank or chamber 8 to the centrifugal pump 10, 11 a passage leading from the force side of said pump into the tube 12 which empties into said tank 4 as illustrated.

13 indicates a passage leading from said tank 4 into the passage 14 joining the suction side of the centrifugal pump 15, and 16 represents a passage from the force side of said pump 15 back into the jacket 1. Said pump 15 is conveniently operated through the belt 17 or other source of power and said pump 10 is conveniently operated through the gears 19 and 20 or other suitable means.

In operation the hot water and steam, or hot water alone is forced by the pressure in the jacket and also by the pump 15 up through the passage 3 into the tank 4 where the level 21 of the liquid is maintained by reason of the location of the filler cap 22 being on said level. In the tank 4 the steam and air readily escape from the level 21 and pass down into the pipe 5 to the passage 6 and through the water tubes 7 into the bottom tank 8, all as is indicated by the arrows. The condensed fluid in the tank 8

is sucked by the centrifugal pump 10 into its suction chamber and any air that may be carried over through the radiator escapes through the vent pipe 25 to the atmosphere. In the meantime any alcoholic vapors which may have been carried over will be absorbed in the condensed fluid and forced along with the water through the passage 11 and pipe 12 back into the tank 4. From the tank 4 the colder lower strata of fluid passes down by gravity through the passage 13 and is sucked by the pump 15 through said passage as well as through the passage 14 into its suction chamber and is forced through the passage 16 back into the jacket and thus the fluid and vapors are circulated around and round the circuit in a manner that will be understood from the drawings. It should be observed, however, that the return pipe 12 is very much smaller in area than are the outgoing passages 3, 5, 7 and 9. It results from this that the total back pressure of the steam in tank 4 that is exerted in pipe 12 is less than is the total pressure in the passages 5, 7 and 9, and therefore, since the pump 10 possesses relatively great power, it can continuously deliver liquid back into said tank 4, against a very considerable back pressure. Consequently the pressure in jacket 1 can be maintained at a point much higher than that due to the atmosphere.

A higher pressure in the jacket 1 results in a higher temperature around the combustion chambers cooled by said jacket and a higher temperature in said combustion chambers enables the operator to burn an inferior fuel with greater facility than is possible at lower temperatures.

Stated in other language, it is well known that there is one particular temperature at which a given fuel mixture will ignite and exert its propulsive powers with the greatest satisfaction and that if this particular temperature can be constantly maintained in an engine in spite of the varying loads and working conditions of that engine a much smoother operation will result than would otherwise be the case.

According to this invention, therefore, due to the above restricted passage 12 the pressure in the jacket is maintained at a point considerably above that of the atmosphere and therefore the temperature around the combustion chambers is maintained at a

point considerably higher than that which would be due to atmospheric pressure in the jacket and from this higher temperature there results the following advantages:—

- 5 Should the load on the engine increase and therefore should the temperature of the combustion chambers increase the excess of heat is immediately passed off in the form of latent heat accompanying the steam generated and this latent heat is dissipated through the radiator 2 without greatly altering the temperature in the jacket. Should, on the other hand, a lighter load be placed on the engine, and the temperature generated
- 10 in the combustion chambers lessened, the higher temperatures of the jacket fluid and of the metal constituting the engine walls would cause heat to flow into said combustion chambers and thus would the temperature of said combustion chambers be counter-balanced.
- 15

In other words, it is obvious that by the employment of the restricted passage 12 in the circuit a more equal temperature can be maintained in the combustion chambers throughout the varying loads and working conditions imposed on the engine than would otherwise be the case; and further, that a higher temperature may be continuously maintained in said combustion chambers. From this it results that one is enabled to burn with more satisfaction an inferior fuel and to continuously obtain a smoother working from the engine than would otherwise be the case.

The construction illustrated is peculiarly adapted for tractors, in that it admits of an unusually strong installation on the forward portion of the tractor, while at the same time functioning in a satisfactory manner. The pump 10 can be readily run at such a speed or can be provided with such a capacity as will force the cooled fluid sufficiently fast through the restricted passage 12 into the tank 4 against the pressure therein to maintain a super-atmospheric pressure in said tank, no matter what this pressure may be, nor how fast the fluid may be condensed, for the condensate may temporarily, accumulate in the tubes 7 without causing any inconvenience. That is, the radiator 2 is not provided with a vent, but is closed to the atmosphere, and therefore, such vent cannot be opened by the accumulation of the pressure as heretofore, and thus relieve the pressure.

It therefore constitutes an important feature of this invention that the delivery 11 of the pump 10 is located between the vent 25 and the supply 9 of fluid from the radiator, for as the fluid accumulates in said radiator, it continues to be sucked through the passage 9, the air continues to escape therefrom through the vent 25, and said air freed fluid can continue to be forced through the pas-

sages 11 and 12 back into the tank 4 against any super-atmospheric pressure that may exist therein.

The pipe 5, as shown, is smaller than the chamber 6 and the area of the passages 7 so that the flow of fluid from tank 4 into the radiator 2 is restricted. This further enables the maintaining of a higher pressure in tank 4 and in jacket 1, than that of the atmosphere, and therefore a higher temperature around the combustion chambers than would accompany an atmospheric pressure in said jacket.

It is obvious that those skilled in the art may vary the details of construction, arrangement of parts and the mode of operation without departing from the spirit of the invention, and therefore, I do not wish to be limited to the above disclosure except as may be required by the claims.

What I claim is:—

1. In a cooling system for an internal combustion engine the combination of a jacket; a radiator; a tank closed to the atmosphere associated with said radiator; means for passing fluid under pressure from said jacket to said tank; means for passing fluid under pressure from said tank into said radiator; means for drawing fluid from said radiator and forcing it under pressure back into said tank; and means for returning fluid from said tank back into said jacket, substantially as described.

2. In a cooling system for internal combustion engines, the combination of a jacket; a radiator closed to the atmosphere; a tank closed to the atmosphere associated with said radiator; means for passing fluid under pressure from said jacket to said tank; means for passing fluid under pressure from said tank into said radiator; means for drawing fluid from said radiator and forcing it under pressure back into said tank; means located away from the radiator for venting to the atmosphere any air that may accompany the condensed fluid; and means for returning fluid from said tank back into said jacket, substantially as described.

3. In a cooling system for an internal combustion engine the combination of a jacket; a radiator closed to the atmosphere; a tank closed to the atmosphere; a connection between said radiator and said tank; a connection between said tank and said jacket; a vent for permitting air to escape to the atmosphere; a pump having its delivery side located between said vent and said radiator; a connection between said pump and said radiator; a connection between said pump and said tank; and means for passing fluid from said tank to said jacket, substantially as described.

4. In a cooling system for an internal combustion engine, the combination of a jacket; a radiator closed to the atmosphere;

a tank closed to the atmosphere; a connection between said radiator and said tank; a connection between said tank and said jacket; a vent for permitting air to escape 5 to the atmosphere; a pump having its delivery side located between said vent and said radiator; a connection between said pump and said radiator; a restricted connection between said pump and said tank; 10 and means comprising a second pump for passing fluid from said tank to said jacket, substantially as described.

5. In a cooling system for an internal combustion engine the combination of a 15 jacket; a tank closed to the atmosphere; a connection between said tank and said jacket; a radiator; a connection between the top of said radiator and said tank; a vent adapted to permit the escape of any air 20 caught in the condensate; a pump located between said vent and radiator; a connection between the bottom of said radiator and the suction side of said pump; a connection between the force side of said pump and said 25 tank; a connection between said vent and said pump; and means for passing fluid from said tank back into said jacket, substantially as described.

6. The process of maintaining the pressure 30 of the fluid in a jacket of an internal

combustion engine above that of the atmosphere, which consists in forcing said fluid under super-atmospheric pressure into a tank; condensing any vapors given off outside of said tank; forcing the condensed liquid thus obtained under super-atmospheric pressure back into said tank venting any air that may be carried over with said condensate; and forcing the condensate from said tank back into said jacket, substantially 35 as described.

7. The process of maintaining the pressure of the fluid in a jacket of an internal combustion engine above that of the atmosphere, which consists in forcing said fluid under super-atmospheric pressure into a tank; condensing any vapors given off outside of said tank; sucking the condensate into a pump chamber; forcing the condensed liquid thus obtained under super-atmospheric pressure back into said tank through a restricted passage; venting any air that may be carried over with said condensate after the liquid reaches said pump chamber and before it is forced back into 55 said tank; and forcing the condensate from said tank back into said jacket, substantially as described.

In testimony whereof I affix my signature.
WELLINGTON W. MUIR.
